UNITED STATES PATENT OFFICE.

WILLIAM T. SHERER, OF CHICAGO, ILLINOIS.

FURNITURE DRAWER.

1,410,769.

Specification of Letters Patent. Patented Mar. 28, 1922.

Application filed April 12, 1920. Serial No. 373,109.

To all whom it may concern:

Be it known that I, WILLIAM T. SHERER, a citizen of the United States, residing at Chicago, in the county of Cook and State 5 of Illinois, have invented a certain new and useful Improvement in Furniture Drawers, of which the following is a specification.

My invention relates to improvements in furniture drawers and the like and has for 10 one object to make a furniture drawer from which leakage of its contents is impossible. Other objects will appear from time to time throughout the specification and claims.

My invention is illustrated more or less 15 diagrammatically wherein:

Fig. 1 is a vertical section of a drawer embodying my construction, with parts broken away;

Fig. 2 is a horizontal section taken at the 20 line 2 2 of Fig. 1;

Fig. 3 is a rear elevation of the drawer with parts broken away;

Fig. 4 is a perspective view of the key bar;

Fig. 5 is a bottom view of a drawer with a 25 modified form of my construction;

Fig. 6 is a vertical section on the line 6 6 of Fig. 5;

Fig. 7 is a vertical section on the line 7 7 of Fig. 5;

Fig. 8 is a view similar to Fig. 1 illustrating a further modified form;

Fig. 9 is a horizontal section on line 9 9 of Fig. 8;

Fig. 10 is a horizontal section on line 10 10 of Fig. 8.

Like parts are indicated by like characters throughout.

A is the front of a furniture drawer having the handle A¹. B is the bottom of such 40 a drawer. C is the rear of the drawer. B¹ B¹ are the sides of the drawer. D is a key bar having in its upper surface the slot D¹ and along one of its sides the second slot D². In the modified form I provide the 45 horizontal extension D³ along the bottom of the key bar. This may be perforated as at D⁴ to allow the insertion of a roller D⁵. In one form of my invention the ends of the key bar D are dovetailed as at D⁶ to fit into 50 the dovetailed slot B³ in the side B₁. The sides B¹ B¹ have the interior slots B² B² adjacent their rear ends. They are also slotted as at B⁴ along their bottom.

When the drawer is assembled the grooves 55 in the key bar will normally be filled

with glue or other adhesive material into which the bottom and the end parts will be thrust.

The use and operation of my invention are as follows:

Heretofore it has been difficult if not impossible to prevent the leakage between the bottom and the sides or ends of furniture drawers. It is of particular importance to prevent such leakage where the drawers are 65 used to contain small granular material and the like. In my construction I provide a key bar slotted along its side which slot fits over the bottom of the drawer. I provide a slot on the upper surface of the key 70 bar into which slot the end of the drawer slides and fits. When this relation of parts is fixed as for example by gluing or nailing them together I make leakage of contents and separation of parts absolutely impossible. In my drawings I have illustrated several modifications. In the form shown in 75 Figures 5, 6, and 7, I provide a forward longitudinal extension of the key bar. One advantage of such a construction is that it 80 provides a convenient means for mounting a roller under the rear of the drawer. Another modification is shown in Figures 8, 9, and 10 wherein the key bar is dovetailed into vertical slots in the rear of the drawer sides. 85 When this form is used the key bar is fitted into these slots, the end of the drawer is also dovetailed and fitted down into the slot in the upper surface of the key bar and the bottom of the drawer is subsequently fitted 90 into the slots in the bottom of the drawer sides and into the slot in the side of the key bar, and, lastly, the front of the drawer is fitted on and secured in place.

Although I have shown in my drawings 95 an operative form of my invention still it will be understood that many changes might be made, both in shape, dimension and arrangement of parts without departing from the spirit of my invention. For example, 100 the modifications of Figures 6 and 9 might be combined. Other changes will readily suggest themselves and I wish therefore that my drawings be taken as in a sense diagrammatic.

I claim—

1. A drawer comprising side, bottom and end members, a key bar provided with two slots, one to engage the end of the bottom member, the other to engage the lower edge 110

of an end member, the side members being dovetailed to engage the edges of the end member and the ends of the key bar.

2. A drawer comprising side, bottom and 5 end members, a key bar across the rear of the drawer, said bar being provided with two slots, one to engage the end of the bottom member and the other to engage the lower end of the rear member, the side members being dovetailed grippingly to engage 10 the edges of the rear member and the ends of the key bar, the side members being slotted at the front to interlock with the front member.

3. A drawer comprising side, bottom and 15 end members, a key bar across the rear of the drawer, said bar being provided with two slots, one to engage the end of the bottom member and the other to engage the lower end of the rear member, the side members being slotted grippingly to engage the edges of the rear member and the ends of the key bar, the side members being slotted 20 at the front to interlock with the front member.

Signed at Chicago, county of Cook, and State of Illinois, this 5th day of April, 1920.

WILLIAM T. SHERER,
